UNITED STATES PATENT OFFICE.

LOOMIS L. KELLY, OF NORFOLK, VIRGINIA, ASSIGNOR TO THE WELLMAN-SEAVIER-MORGAN COMPANY, OF CLEVELAND, OHIO, A CORPORATION OF OHIO.

SIDE-WALL TRAVELER.

Application filed October 14, 1920. Serial No. 416,863.

To all whom it may concern:

Be it known that I, LOOMIS L. KELLY, a citizen of the United States, residing at Norfolk, in the county of Norfolk and State of 5 Virginia, have invented certain new and useful Improvements in Side-Wall Travelers, of which the following is a specification.

This invention relates to side wall travelers and has among its objects to provide an improved mechanism whereby material such as coal or ore may be conveyed from any one of a series of pockets or bins to a receptacle positioned alongside of the structure 15 containing the pockets or bins. The invention consists of the formation, combination and arrangement of parts as will be herein described and particularly claimed.

The invention is intended primarily for 20 use in connection with piers for the loading of material such as coal or ore into vessels berthed alongside of the pier or dock. Such piers are usually arranged with elevators for hoisting drop bottom cars to a deck of 25 the pier at considerable height above the vessel. The material is dumped from the cars into pockets or bins formed in the pier whence it may fall by gravity or be otherwise conveyed to the vessel. The deck of the 30 pier and the pockets are necessarily at a fixed elevation. The vessels to be loaded are of varying heights. The change in tide also requires means for conveying such materials to be adjustable vertically. It is further 35 desirable that the conveying apparatus be adjustable along the pier and laterally with respect to the pier, in order that the varying positions of loading hatchways may be accommodated. The present 40 apparatus is arranged to provide all such flexibility and at the same time to handle the material in a satisfactory and economical manner.

In the drawings, which show a preferred 45 embodiment of the invention, Figure 1 is an end elevational view of the side wall traveler of my invention, the cross sectional construction of the dock and pier being shown in dotted outline. In this figure the extreme 50 positions of the laterally extending material chute are also shown in dotted lines. Figure 2 is a side elevational view of the traveler, various portions of the pier being shown in dotted outline in this figure also. 55 Figure 3 is a horizontal section taken

through the traveler on the line AA of Figure 2. Figure 4 is a vertical sectional view through the vertical leg of the apparatus, this view being taken on the line CC of Figure 6. Figure 5 is a transverse sectional view taken on the line BB of Figure 4. Figure 6 is a front elevational view of the vertical leg of the device detached from the frame and other related parts.

Referring to the accompanying drawings, 60 the numeral 17 denotes the face of the dock against which vessels to be loaded are berthed. The frame work of the pier is shown in dotted outline and is denoted by the numeral 18, the pier having one or more 65 tracks 25 on its top deck for the accommodation of material cars. The numeral 16 denotes one of a series of pockets located beneath the material track 25 and into which the coal or other substance is dumped from 70 the car. The pockets 16 are arranged longitudinally along the pier and have inclined bottoms so that the material will fall by gravity through suitable discharge gates such as 22 at the lower and outer extremity 75 of each pocket. Such construction of pier and pockets is in common use where material in bulk is loaded into vessels.

The present invention has to do with 80 means for receiving the material from one of the pockets 16, through the discharge gates 22, and delivering it in a convenient and satisfactory manner into the hatch of a vessel positioned alongside of the dock 17. In my previous application, Serial #403,280, 85 filed August 13, 1920, I have shown and described a mechanism co-operating with a similar arrangement of pier for delivering material into the hold of a vessel through a power operated mechanical trimming machine. The present device is intended primarily for the delivery of coal, by gravity, 90 into open hatches, and without the use of a trimming machine. The use of travelers of the present type is contemplated along piers 95 equipped with machines of the former type, the former machines to be used principally for delivering cargo coal. Bunker coal is ordinarily delivered through open hatchways and bunker trimming must be done by hand, whereas cargo trimming is now done by machinery with a great saving of labor. It is therefore expected that the runways 100 shown as applied to the pier in my previous application may be utilized for the accom- 105 plishment of the trimming of the cargo. 110

modation of the present side wall traveler. It being understood that a plurality of pockets 16 is provided on such piers, the present arrangement of traveler is arranged 5 adapted to serve any one of such pockets. To this end a vertical plane girder 21 is supplied for the active length of the pier. Upon the top of this girder is a runway rail 26 which accommodates the traveler wheels 10 8. These latter carry all of the vertical load of the traveler. A continuous girder 20, lying in a horizontal plane, is also supplied near the top of the pier, the same having a runway rail 27 on its inner face for 15 the accommodation of the horizontal thrust wheels 9 which are carried by the traveler frame. Near the base of the pier is a continuous horizontal girder 19 which accommodates horizontal thrust wheels 10, these 20 latter being provided to resist the horizontal thrust at the bottom of the traveler frame.

The traveler embodies a main trussed structure or frame 1, which has suitable 25 brackets or extensions 28 and 29 for the accommodation of the aforesaid wheels 8, 9 and 10. The frame is arranged along the side of the pier in a substantially vertical fashion and may be propelled by any suitable 30 means along the runway rails into position in front of any one of the pockets 16. The detail construction of this frame is immaterial so long as it properly accommodates the various operating features of the 35 device, but it is preferably arranged with lattice sides and an open center portion, the coal chutes and handling machinery for the same being arranged in this central portion. By this arrangement the traveler may 40 be made of light weight and at the same time is best adapted to accommodate the machinery and to resist the various forces and moments set up in the structure.

The coal handling mechanism consists primarily 45 of a vertical leg 2 which is secured to and carried by the frame 1. This leg is so located laterally of the pier that when the traveler is moved along the pier the open top of the leg 2 will register with one 50 or another of the aligned discharge openings controlled by the gates 22. The leg 2 is arranged to slidably accommodate within its walls a vertically-movable sliding-box 4. This vertical leg has a normally open front 55 face and by a system of plates 31 carried upon the top of the sliding-box 4, and arranged to travel in suitable ways 32 in front of the leg 2, the active portion of the leg 2, or in other words the portion of the leg 60 above the sliding-box, will always be closed at the front by means of the said plates, irrespective of the position of the sliding-box. The sliding-box 4 may be moved to any position vertically of the leg 2, the 65 drum 7 and the cable 12 being supplied for

this purpose. This cable 12 passes over suitable guide sheaves 13 and 14 and around equalizer sheaves 15, attached to an equalizer lever 33, which is in turn attached to the sliding-box 4 by means of links 34.

The sliding box may thus be raised or lowered by means of the drum 7 and the cable 12, which are carried by and with the frame 1. As the sliding box is raised, the various plate sections forming the front 75 of the leg 2 are picked up in serial fashion. When the sliding box is lowered, the sections of the front are also lowered, one at a time coming to rest upon properly positioned lugs 35 arranged within the guides 32 for 80 this purpose.

The discharge opening in the lower end of the sliding box 4 is controlled by means of a coal gate 5, a drum 24 and cable 23, carried by the frame, being provided to 85 manipulate this gate. An outwardly extending discharge chute is suspended at its inner end from the plate 39 which forms 90 part of the sliding box 4. This is accomplished by means of the cables 37 which are affixed at their upper end to brackets 36 carried by the sliding box plate 39. The lower ends of cables 37 are wound around cams 38 which are attached to the inner 95 end of chute 3, this arrangement allowing the inner end of chute 3 to adjust itself to different positions. The cables thus allow the outer end of the chute to be swung in a horizontal plane, a suitable abutment rocker 30 being arranged for the bearing 100 of the chute against the sliding box.

The outer end of the chute 3 is operated and adjusted by means of a cable 11 which is wound upon a drum 6 carried by the frame 1. The outer end of the chute 3 may 105 thus be drawn up into a position substantially parallel with the frame 1 or may be lowered into an outstanding or sloping position so that the coal or other material will 110 travel down this chute by gravity and be discharged into the hatchway. The inner end of the chute 3, being carried upon the sliding box 4, is adjustable vertically with the same.

In practice the traveler is propelled along the runways until the vertical leg 2 is positioned directly under the desired pocket 16. The sliding box 4 is then lowered, carrying with it the inner end of the chute 3, and the outer end of the chute 3 is also lowered, 115 by means of the cable 11, until the outer end of the chute 3 is in the vertical position desired for the particular height of vessel to be loaded. The outer end of the chute 3 is then swung in a radial fashion 120 to bring it immediately over the hatchway of the vessel, and by means of the gates 22 and 5 the flow of material to the vessel may be controlled. When it is desired to move 125 the traveler from one pocket to another, 130

chute 3 is drawn up as heretofore described, when it will clear the superstructure of the vessel and can therefore be moved along side of the same.

5 I have thus described an embodiment of my present invention. Various changes and modifications are contemplated, within the scope of the appended claims, without departing from the spirit thereof.

10 What is claimed is:

1. In a side wall traveler, a pier having longitudinally arranged material pockets, a frame movable along the pockets, the same carrying a fixed gravity leg arranged to 15 register with the discharge openings of the pockets and to receive material therefrom, an outwardly extending chute arranged to receive material from the gravity leg and to discharge it at a point removed laterally 20 from the pier, and means carried upon the said movable frame for the vertical and lateral adjustment of the last named chute.

2. In a side wall traveler, a series of longitudinally arranged material pockets, 25 each having a discharge opening, a frame movable along the pockets, a gravity leg carried by the frame, the upper end of the same being in transverse alignment with the material pocket discharge openings, a 30 gravity chute adapted to receive material from the gravity leg and extending out-

wardly therefrom, the same being adjustable vertically along said leg and the outer end being adjustable vertically and laterally independently of the inner end of the same. 35

3. In a side wall traveler, a pier having longitudinally arranged material pockets, runways arranged along the pier in front of the pockets, a frame having load carrying wheels and thrust wheels operative upon the runways, and material-handling chutes carried by the frame and arranged to receive material from any of the pockets and convey it therefrom, said chutes being adjustable vertically on the frame, the said 40 frame embodying trussed side legs and an open central portion, the conveying elements being arranged in the said open central portion.

4. In a side wall traveler, a pier having longitudinally arranged material pockets, a frame movable along the pockets, the same carrying a fixed gravity leg arranged to register with the discharge openings of the pockets and to receive material therefrom, and a conveyor adjustably mounted on the frame and arranged to receive material from the gravity leg and to discharge it at a point removed laterally from the pier. 55

In testimony whereof I affix my signature. 60

LOOMIS L. KELLY.
